UNITED STATES PATENT OFFICE.

GEORGE C. CHERBONNIER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-DOOR OPERATING AND CONTROLLING MECHANISM.

1,244,699.

Specification of Letters Patent. Patented Oct. 30, 1917.

Application filed February 1, 1917. Serial No. 145,879.

To all whom it may concern:

Be it known that I, GEORGE C. CHERBONNIER, residing at city of St. Louis, State of Missouri, and being a citizen of the United States, have invented certain new and useful Improvements in Car-Door Operating and Controlling Mechanism, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, and it is obvious that various modifications thereof, within the scope of the claims, will occur to persons skilled in the art.

In said drawings:

Fig. 1 is a side elevation of an end portion of a railway car, showing one of a number of dumping doors, a shaft for controlling the position of the doors, means connecting the doors to the shaft and shaft operating and controlling mechanism in edge view, the same being applied to the end of the car;

Fig. 2 is a somewhat enlarged view showing a portion of the car in end elevation and a portion in section to disclose the hopper and one of the doors, the operating and controlling mechanism being shown in elevation and as attached to the end of the car;

Fig. 3 is a view on a considerably larger scale showing the operating and controlling mechanism in front elevation and as attached to the end of the car;

Fig. 4 is a view of the operating and controlling mechanism most of which is shown in edge view and as applied to the end sill of the car; and

Fig. 5 is a view similar to Fig. 3 but showing the controlling portion of the mechanism in active coöperation of the ratchet wheel carried by the winding shaft.

The present invention relates to shaft operating and controlling mechanism and its especial aptitude for association with the doors of a dump car makes it highly advantageous to install it in railway cars of this general type wherever the construction of the car will permit of its inclusion.

Ballast cars have drop doors, an excellent

control over which is furnished by the operating mechanism herein disclosed, which mechanism is capable of being under the control of the operator at all times during the discharge of the load.

Dump car doors that are connected by chains to the winding shaft and that drop by gravity in opening, subject those chains to heavy disrupting stresses when upon release, they fly open and come to a sudden stop as the chains become fully unwound. In instances where the doors encounter stops before the chains are completely unwound, the heavy load on the doors tends to cause the latter to tear the stops from their supporting structure.

It is a purpose of this invention to provide mechanism in which there is a shaft and means connecting the shaft with a series of dumping doors, proper actuation of the shaft causing said means to close the doors or to permit them to open by gravity, according to the direction of rotation of the shaft. To this end, means are provided for driving the shaft in one direction to so close the doors, which means may automatically, and by gravity if desired, place itself in non-driving relation to the winding shaft when the doors are closed, or when they are in the course of opening.

Controlled regulation of the speed of the doors in moving from one position to the other is provided for. There is, consequently, no danger to the operator of the door-operating mechanism such as is common where the winding shaft is uncontrolled in unwinding and revolves rapidly so that the winding means also revolves violently to the imminent danger of the operator.

The peculiar arrangement and operation of articulated pawls which are preferably present in the control means, furnishes an economical and highly satisfactory shaft-retarding means, and a device is so associated with these pawls that they are capable of preventing unintentional actuation of the shaft, locking the doors in closed position.

Other features of novelty and merit appearing hereinafter are to be regarded as coming within the spirit and scope of the present invention.

Referring specifically to the parts, 10^a represents the side sill of a ballast car, a sufficient portion of the body of which is illus-

trated in Figs. 1 and 2 to clearly indicate the location of the various parts later referred to. Somewhat below side sill 10^a is located a winding shaft 11 which extends parallel with side sill 10^a for any convenient distance longitudinally of the car. Arranged longitudinally of shaft 11 is a series of dumping doors 12, only one such door being shown in Fig. 1. Doors 12 have their outer ends connected to winding shaft 11 by chains 13 adapted to be wound upon shaft 11 to draw the doors upwardly into closed position.

At the right hand end of shaft 11 in Figs. 1 and 4, a ratchet wheel 14 is shown as being mounted. Said shaft is preferably non-circular at its end as is the aperture in ratchet wheel 14 through which the shaft passes, thereby insuring that rotation of the ratchet wheel will cause a like rotation of shaft 11. The outer side of ratchet wheel 14 has projecting therefrom a hub 14^a over which is slipped a sleeve 27^a of an oscillatory member 27 provided at its free end with a socket 27^b, into which a crowbar or other lever 27^c may be inserted by means of which member 27 may be oscillated on the hub 14^a of wheel 14. Attached to socket portion 27^b of oscillatory member 27 is a pawl 29 mounted upon a pivot pin 28 and 30 there retained by a washer and the outer upset end of said pivot pin 28.

As best shown in Fig. 5, the lever 27^c may be raised and lowered, and when in its raised position, the pawl 29 will be in the position shown principally in dotted lines in Fig. 5 wherein it bears against one of the teeth of ratchet wheel 14. As lever 27^c is moved downwardly, ratchet wheel 14 is given a counterclockwise rotation, resulting in such 40 a rotation of winding shaft 11. Chains 13, shown in Figs. 1 and 2, thereupon are wound upon shaft 11 and the doors are raised to their upper or closed positions by the continued oscillation of lever 27^c.

45 It will be noted that the end of shaft 11 passes through a bracket 30, the upper end of which is secured to the lower portion of the end sill 10, and in Figs. 3 and 4 it is seen that another bracket or plate 31 is riveted in its upper portion to bracket 30 just below the bottom flange of end sill 10. Bracket or plate 31 is bent to have a Z-shaped cross section, the portion below the horizontally disposed intermediate part of plate 31 being apron-like and of considerable area. Connecting plate-like bracket 30 and the apron portion of plate 31 are pins 17 and 22, which are shown as having thin heads and shanks passing through both 50 brackets 30 and 31, washers being inserted upon the ends of these pins which project through bracket 30 and cotter pins passing through the pin ends outside of the washers, permanently fixing pins 17 and 22 in position. Mounted upon pin 17 and being

housed and protected by bracket plates 30 and 31, is a pawl 16 provided with a tooth or pallet 18 adapted to engage with the teeth of ratchet wheel 14. Said pawl 16 is also jaw-shaped near its free end to have a 70 recess 19.

Pivottally mounted on pin 22 is another pawl 21 which also is provided with a single tooth or pallet 23 intended to engage with the teeth of ratchet wheel 14. Pawl 75 21 has preferably integrally formed therewith, a lever or handle 21^a projecting toward the side of the car. Projecting inwardly in the opposite direction is a finger 20, which, by choice, is also an integral part 80 of pawl 21. The free end of finger 20 is provided with a rounded lip 19^a adapted to enter the recess 19 in the jaw-shaped portion of pawl 16. It is thus plain that pawls 16 and 21 are articulated in such manner 85 that movement of one produces a movement of the other. Such movement is, of course, simultaneous, but the single tooth or pallet of each pawl is reversely acting with respect to that of the other, so that when one 90 pawl tooth is in full engagement with ratchet wheel 14, the other is out of contact therewith.

Assuming that the doors are opening under the influence of gravity, and that the 95 locking device of the articulated pawls hereinafter referred to is in a noneffective position, it will be understood that the tooth of one of the detents is momentarily in full contact with one of the teeth of ratchet 100 wheel 14, while the other is completely out of contact with said ratchet wheel teeth. Ratchet wheel 14 causes, say, pawl tooth 23 to be pushed out of engagement with the tooth against which it is resting, and while 105 this is occurring the tooth or pallet 18 of pawl 16 is approaching one of the faces of another of the ratchet wheel teeth. In turn, tooth 18 of pawl 16 is forced out of engagement with the ratchet wheel by a following tooth thereof and tooth 23 or pawl 21 again approaches another tooth of ratchet wheel 14, this alternate and reverse action of the pawls 16 and 21 and their teeth 18 and 23 continuing during the rotation of ratchet 115 wheel 14 as the latter responds to the turning of the shaft, which is caused by the doors unwinding the chains 13 as they drop by gravity to their open positions. The teeth or pallets 18 and 23 of pawls 16 and 21 are so spaced that they engage the teeth of ratchet wheel 14 upon said ratchet wheel being moved about one-half the pitch distance of its teeth. Thus the unwinding of chain 13 is accomplished in a series of very 120 short steps, each of which approximates one-quarter the circular pitch distance of the teeth of ratchet wheel 14.

125 A feature of the device is the varying relative speed movements of pawl teeth 18 130

and 23. This feature permits the use of a greater number of teeth in the ratchet wheel than would be possible were the movements of the pawls timed to a constant ratio.

5 The varying ratio in the speed of the pawls is brought about by camming one or both of the interengaging surfaces 18^a and 19^b of the respective pawls. In the drawings the interengaging surfaces of both 10 pawls are shown cammed.

Assuming the load to be discharging, the weight thereof and of the supporting doors will cause rotation of the shaft ratchet wheel 14. This movement of the ratchet will cause 15 the pawl tooth in engagement therewith to be forced outwardly until it clears the ratchet while the other pawl tooth approaches its ratchet engaging position; but since one ratchet tooth clears its respective 20 pawl when another tooth is only one-quarter of the pitch distance from the remaining pawl, it is desirable that the speed of the pawl moving away from the ratchet be greater at the beginning of said movement 25 than at its close thus giving the other pawl an opportunity to enter its ratchet engaging position without packing against the teeth of the ratchet.

It may readily be the case that it is not 30 desired to fully open the doors, but on the contrary to make a restricted opening for a limited discharge of the lading contained in the car. The operator may, to accomplish this desired result, press downwardly 35 on handle 21^a forcing tooth or pallet 23 of pawl 21 into the space between the two nearest teeth to pallet 23. By holding lever 21^a down, ratchet wheel 14, and consequently shaft 11 and the doors, will be held 40 from further movement. Should the opening of the doors be considered too small, he may raise handle 21^a of pawl 21 and allow such further rotation as may be considered necessary. Thereafter he may swing the 45 locking dog 24, which is hung upon bolt 26 that passes through and is secured to bracket 30, to the position shown in Fig. 3, after which he may, if he desires, walk away from the operating mechanism and the same will 50 be locked against further movement. It will also be understood that when the doors are in their fully closed position, tooth 23 of pawl 21 may be similarly caused to engage the teeth of ratchet wheel 14 and locking dog 24 positioned as shown in Fig. 3, whereupon the doors will be held locked 55 and may so remain while the car is in transit.

Toward the pivoted portion of pawl 21, the upper side of handle 21^a is given a peculiar configuration wherein there is a curved seat 25^a conformed to the curved free end 25 of locking dog 24. When the locking dog is in the position shown in Fig. 3, the curved surfaces 25 and 25^a of dog 24 and handle 21^a, respectively, are con-

centric with the axis or center of rotation of said dog 24. That dog 24 may not pass beyond its locking position, the upper side of handle 21^a of pawl 21 is provided with a projection or lug 25^b.

70 As shown in Fig. 5, when it is desired to operate the articulated pawls 16 and 21, dog 24 is swung clockwise from the position shown in Fig. 3 to the position shown in Fig. 5 wherein it lies and rides upon the projection 25^b of handle 21^a.

75 Figs. 3 to 5 inclusive show that the mechanism for operating and controlling shaft 11 is compactly arranged, the ratchet wheel 14, oscillatory member 27, the pawl it carries, articulated pawls 16 and 21, and the locking dog 24 being so mounted as to be protected by the plate brackets 30 and 31 which constitute a type of housing for the parts enumerated. Ratchet wheel 14, as 80 shown in Fig. 4, lies on one side of bracket plate 30 and the oscillatory member, as previously stated, has a sleeve portion 27^a fitting over the hub 14^a of ratchet wheel 14. Said ratchet wheel and oscillatory member 85 27 are kept in position with reference to their longitudinal relation to shaft 11, which shaft is shown as extending through bracket 30 and ratchet wheel 14 to extend beyond sleeve 27^a of oscillatory member 27, by any 90 suitable means. Such means may be that illustrated in Figs. 3 and 4 wherein ratchet wheel 14 is shown to abut bracket plate 30 so as to be incapable of movement toward the left in that figure. Sleeve 27^a of oscillatory member 27 may be kept from movement toward the right by a washer 32^a of greater diameter than the hub 14^a of ratchet wheel 14, a U-shaped keeper 32 embracing shaft 11 outside of washer 32^a. The insertion of a cotter pin 33 through keeper 32 and shaft 11 will prevent withdrawal toward the right in Fig. 4 of washer 32^a, hub 14^a of ratchet wheel 14 and sleeve 27^a of oscillatory member 27. On the left hand 100 side of plate bracket 30, a washer 34^a surrounds shaft 11 and is held in place by a cotter pin 34 passing through shaft 11. It is thus seen that all of the parts that are directly related to shaft 11, are maintained 105 in correct longitudinal position with reference to the same.

The *modus operandi* is as follows:

The doors having been swung down to their open position, as illustrated in dotted lines in Fig. 2, and lading having been discharged, said doors may be returned to their closed position by arranging the locking dog 24, as shown in Fig. 5, so that it will lie against and be adapted to ride on projection 25^b of lever 21^a of pawl 21. A suitable lever 27^c is then inserted in the socket 27^b to oscillate member 27 and the latter is oscillated to be brought into the raised position shown in Fig. 5. As it approaches the posi- 115

tion shown in that figure, pawl 29 carried thereby will slip between a pair of teeth of ratchet wheel 14 and bear upon what is then the upper surface of one of said teeth. Said lever 27^c is then vibrated up and down, and upon each down stroke it will force ratchet wheel 14 counterclockwise to a certain extent. At the completion of each down stroke of lever 27^c, oscillatory member 27 will assume approximately the position it is shown in in Fig. 3, whereupon pawl 29 will by gravity assume the position illustrated in that figure coming entirely out of contact with ratchet wheel 14. As oscillatory member 27 is again brought back to the position illustrated in Fig. 5, gravity will influence pawl 29 so that it will tend to swing toward the teeth of ratchet wheel 14, ultimately slipping between a pair of such teeth in assuming its upper position, as shown in Fig. 5. This operation is continued, ratchet wheel 14 rotating shaft 11 to which it is fixed, thereby winding the chains 13 upon said shaft and raising the doors 12 to their upper or closed positions.

During this winding operation, the teeth of ratchet wheel 14 are alternately acting upon the single teeth of pawls 16 and 21 causing them to alternately engage the ratchet wheel teeth and release the same, the articulated connection between pawls 16 and 21 causing their teeth or pallets to be reversely acting.

Doors 12 having been brought to their closed positions as indicated, lever 21^a may be pressed downwardly so that tooth 23 of pawl 21 will press against one of the teeth of ratchet wheel 14, as shown in Fig. 3. Thereafter, locking dog 24 may be swung from the position shown in Fig. 5 to that illustrated in Fig. 3 and said pawl 21 will be incapable of retraction from the teeth of ratchet wheel 14. By reason of the articulated connection between pawls 16 and 21, pawl 16 will be held definitely out of contact with the teeth of ratchet wheel 14 and both pawls 16 and 21 will be immovable. It is also obvious that ratchet wheel 14 can no longer turn while this locked condition prevails, and hence shaft 11 cannot turn to unwind chains 13, doors 12 being securely locked in place as the result. Lever 27^c illustrated in Fig. 5, may then be withdrawn from the socket portion 27^b of oscillatory member 27, which oscillatory member will automatically assume the depending position shown in Fig. 3. Pawl 29 carried by oscillatory member 27 will by gravity automatically assume the position illustrated in Fig. 3 where it is out of contact with ratchet wheel 14.

The car having been again loaded and sent to a place where the load is to be discharged, all that is necessary, under ordinary circumstances, to open the doors is to

press down on handle 21^a of pawl 21 and to swing locking dog 24 to the position illustrated in Fig. 5. The weight of the doors, augmented by the portion of the load they sustain, will give a downward pull on chains 13 which will revolve winding shaft 11. Locking dog 24 having been positioned as stated, the teeth of ratchet wheel 14 immediately act upon the individual teeth or pallets of pawls 16 and 21 causing the same to alternately move into and out of contact with the ratchet wheel teeth. Engagement of the ratchet wheel teeth by either tooth 18 of pawl 16 or tooth 23 of pawl 21, will check the rotative action of the ratchet wheel but the latter will operate said pawls so that there will be a continuous but step-by-step unwinding rotation of shaft 11 until the doors have reached their fully open position. Should it not be desired to fully open the doors, the operator may, at any time during the course of their opening, press down on lever 21^a of pawl 21 and thereafter position locking dog 24 as illustrated in Fig. 3. The parts will then be in the position depicted in that figure and shaft 11 will be held against further rotation, tending to allow the doors to open.

It is therefore manifest that said doors may be regulated not only as to the speed at which they may open, but also to the degree of opening they permit. This is useful when it is desired to distribute the load along a roadbed, only such amount of lading being allowed to escape at one point as may be desired. Furthermore, any amount of lading may be discharged at a single point, or all of the lading may be discharged at once.

What I claim is:

1. In combination in a car or other structure, a door and door operating mechanism comprising a winding shaft, means connecting said shaft to said door, a device mounted for actuation with said shaft, means co-operative with said device to drive said shaft adapted to be arranged to permit said shaft to turn independently thereof, and articulated members alternately effective to regulate the movement of said device. 105

2. In combination in a car or other structure a door and door operating mechanism comprising a winding shaft, means responsively connecting said shaft and door, a toothed device secured to said shaft, means operable to actuate said device to drive said shaft adapted for automatic disassociation with said device and articulated reversely-acting members alternately co-active with said device to regulate its action. 110

3. In combination in a car or other structure, a door and operating mechanism therefor comprising a winding shaft, means responsively connecting said shaft and door, a ratchet wheel secured to said shaft, more 120

- than two pawls adapted to engage the teeth of said ratchet wheel, some of said pawls having separate fulcrums and being reversely operable to alternately engage the 5 ratchet wheel teeth, said ratchet wheel being adapted to be pawl-driven while the reversely operable pawls are acting.
4. In combination in a mechanism of the class described, a winding shaft, a ratchet wheel secured thereto, a member free to turn about said shaft, a pawl carried thereby, means with which to turn said member, said pawl being adapted to drive said ratchet wheel, a plurality of articulated reversely- 10 acting pawls responsive to said ratchet wheel and means for independently controlling said articulated pawls and consequently said shaft.
5. In combination in a mechanism of the 15 class described, a winding shaft, a ratchet wheel fixedly secured thereto, a member revolvably mounted on said wheel, a pawl operable by said member to drive said wheel, and a plurality of simultaneously operable separate ratchet wheel-retarding pawls effecting a step-by-step rotation of said wheel.
6. In combination in a mechanism of the 20 class described, a ratchet wheel, a shaft passing through and beyond the same, a member mounted to turn about said shaft, a non-shaft-surrounding shaft-embracing keeper secured to said shaft retaining said member, a wheel-driving pawl carried by said member and a plurality of articulated 25 pawls operable one by the other to alternately co-operate with said ratchet wheel and effect a step-by-step rotation thereof.
7. In combination in a mechanism of the 30 class described, a suitably supported bracket, a winding shaft having a bearing therein, a ratchet wheel adapted to turn with said shaft, means for driving said wheel in one direction, separately formed pawls, individual bracket-supported fulcrums therefor 35 and means so connecting said pawls that they engage and disengage said wheel one after the other and effect a step-by-step rotative control thereof.
8. In combination in a mechanism of the 40 class described, a suitably supported bracket, a shaft passing through the same to extend from opposite sides thereof, a ratchet wheel mounted on said shaft at one side of said bracket to turn with said shaft, a member adjacent said wheel adapted to turn about 45 said shaft, a wheel-driving pawl carried by said member, means co-acting with said bracket, member and shaft to keep the last three mentioned elements and said wheel in co-operative relation and articulated pawls 50 co-acting with said wheel for a step-by-step control of said shaft.
9. In combination in a mechanism of the 55 class described, a suitably supported winding shaft, a ratchet wheel secured thereto to turn therewith, a lever-receiving oscillatory member pivotally mounted on said ratchet wheel, a ratchet wheel-driving pawl carried by said member and jointed mechanism adapted to alternately engage said ratchet 60 wheel in different places to effect a step-by-step control of said ratchet wheel and shaft.
10. In combination in a mechanism of the class described, a winding shaft, a ratchet wheel rotatable therewith, an oscillatory 75 member revoluble about the shaft, a ratchet wheel-driving pawl carried by said member caused by movement of the latter to automatically engage and disengage said ratchet wheel at appropriate times, and step-by-step 80 control mechanism comprising separate members operable one from the other to alternately co-act with said ratchet wheel.
11. In combination in a mechanism of the 85 class described, a shaft, a ratchet wheel rotatable therewith, a suitably mounted oscillatory member, a ratchet wheel-driving pawl carried thereby operable by said member to engage and to move out of contact with said ratchet wheel by gravity, and step-by-step 90 control mechanism comprising a plurality of articulated pawls alternately and reversely operable to co-act with said ratchet wheel.
12. In combination in a mechanism of the 95 class described, a shaft, a ratchet wheel rotatable therewith, means adapted to co-act with said ratchet wheel to actuate said shaft and a shaft-rotation control mechanism comprising a plurality of separately mounted pawls arranged to co-act with said ratchet 100 wheel, means causing said pawls to be operable one from the other, and means by which an operator may regulate the action of said control mechanism at will.
13. In combination in a car, a sill, a door 105 and operating and controlling mechanism therefor comprising a bracket secured to said sill, a winding shaft, operable means connecting said shaft and door, a ratchet wheel rotatable with said shaft, means for driving 110 said shaft and ratchet wheel in one direction, said shaft and wheel being oppositely operable by said door, articulated pawls separately mounted on said bracket co-operative with said ratchet wheel in either of its 115 directions of movement to render such movement a step-by-step action, one pawl being provided with a lever, and means adapted to co-act with said lever to lock said mechanism.
14. In combination in a car, a door and operating and controlling mechanism therefor comprising means for effecting the opening and closing of said door including a ratchet wheel, a plurality of separately mounted 120 pawls one being provided with a lever, means causing said pawls to have simultaneous movement, said pawls being adapted to alternately check and release said ratchet wheel during its rotation and means co- 125 opera- 130

tive with said lever at will to lock said pawls and ratchet wheel against movement.

15. In combination in a mechanism of the class described, a shaft, means for rotating the same, a ratchet wheel fixed on said shaft, a pawl adapted to engage and disengage the ratchet wheel teeth and having a lever, and a pivotally mounted locking dog adapted to engage said lever to cause said pawl to lock 10 said ratchet wheel against movement, said dog and lever having mutual engagement portions concentric with the pivotal axis of said dog when said pawl is locking said ratchet wheel.
- 15 16. In combination in a mechanism of the class described, a shaft, means for rotating the same, a ratchet wheel fixed on said shaft, a ratchet wheel-engaging-and-disengaging pawl provided with a lever, a pivotally mounted locking dog, said dog and lever 20
- having mutual engagement portions adapted to be arranged concentrically to the pivotal axis of said dog to cause said pawl to lock said ratchet wheel against movement, and a stop for said dog on said lever, the dog being 25 adapted to ride on said stop to permit the rotation of said ratchet wheel.
17. In combination in a mechanism of the class described, a shaft, means for rotating the same, a ratchet wheel fixed on said shaft, 30 a pair of pawls one being recessed and the other pawl having a finger entering the recess of the first mentioned pawl to form such a responsive connection between said pawls that said ratchet wheel when turning alternately operates said pawls, the latter regulating the rotation of said ratchet wheel. 35

In witness whereof I have hereunto set my hand.

GEORGE C. CHERBONNIER.
